(57) **CLAIM**

The ornamental design for a chair, as shown and described.

DESCRIPTION

FIG. 1 is a rear perspective view of a chair showing the claimed design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a cross-sectional view taken along line 8-8 in FIG. 2; and,

FIG. 9 is a cross-sectional view taken along line 9-9 in FIG. 2.

In the drawings, portions of the chair shown in broken lines form no part of the claimed design.
